UNITED STATES PATENT OFFICE

ALBERT TACKE, OF RHEINE IN WESTFALIA, GERMANY

DRIVING GEAR FOR DRUMS

Application filed January 3, 1930, Serial No. 418,394, and in Germany January 3, 1929.

My invention relates to improvements in electric individual drives of rollers and the like.

For the electric individual, sectional or separate drive of rollers, calenders, drums, cylinders and the like a reduction gear is frequently required since the operating speed of the roller is generally considerably lower than that of the driving motor. The arrangement of this gear presented up to now considerable difficulties particularly if it is necessary to introduce heating steam, a cooling medium, a boiling liquid or the like into the interior of the drum through an axial bore in its journal or trunnion for the purpose of heating or cooling the shell of the drum, for instance in drier cylinders of paper making machines. The space requirement of the driving motor and the gear was up to now also very considerable so that it was almost impossible to connect an electric drive to an existing machine to be driven.

My invention consists of a reduction gear for an electric individual drive of rollers and the like which eliminates the defects of the hitherto known drives. In my improved drive, the driving wheel of which is mounted on a protruding shaft end of the roller, the gear case rests upon the hub of the gear wheel and is supported further on the supporting frame of the roller. The gear case may preferably be connected to the motor frame in place of the usual end-shield at the drive end in the manner of the well known geared motors so that the space requirement of the motor and the gearing becomes very small.

To facilitate the connection of the gear to the drum, the motor with the gear may be moved into the desired position around the shaft end of the roller, and be fixed in the desired position by a support engaging the frame of the motor or the gear case. This support is preferably effected by means of a stud mounted on the bearing frame of the roller which engages an eye on the motor frame or which is secured in an eye of the gear case and engages a cast or screwed on eye on the bearing frame of the roller. The gear case may consist of two parts the joint

of which coincides with a plane laid through the axes of the gear wheels, for instance, or forms any desired angle with this plane.

In the drawings affixed to my specification:

Fig. 1 represents a longitudinal section 55 through one embodiment of my invention, on the line 7—7 in Fig. 2.

Fig. 2, a front elevation of Fig. 1.

Fig. 3, a modification of a detail in sectional side elevation, and 60

Fig. 4, a similar view of a further modification.

Like numerals of reference indicate like parts in all the figures of the drawings.

Referring to Fig. 1 it will be seen that the 65 electric motor 11 drives the drum 16 through a double step spur wheel train 12, 13, 14, 15. The spur wheel or gear 15 of the second gear step is mounted on the shaft end 17 of the drum 16 and is keyed to it by a key 18. The 70 shaft stud 17 is extended further out and is provided with a continuous axial bore 19 through which steam may be conducted into the drum 16 assuming that this drum is being employed as drier cylinder of a paper making 75 machine. The gear is enclosed by a case consisting of the two parts 20 and 21 which by means of an interposed flanged cover 22 is flanged on to the frame of the motor 11 so that the axial length of the gear connected 80 to the motor 11 is very short. The joint 23 of the two constituent parts of the gear case is in the embodiment illustrated in Fig. 2 of the drawings located in a plane placed through the centers of the axes of the gear 85 wheels and the motor, but it will be understood that it may be located at any desired angle to this plane. By removing one of the halves of the gear case the entire gear may thus be rendered accessible for inspection or 90 repair without the necessity of dismounting any other parts of the gear. The gear case with the electric motor 11 is located close to the framework 30 supporting the bearing 29 of the drum 16. The gear case is supported on the bearing frame 30 by means of a stud 25 mounted on the bearing frame of the drum and engaging an eye 24 on the gear case. 95

The cover 22 serves at the same time as an end plate for the motor 11, and is for this 100

purpose provided with a bearing 26 for the motor shaft 10 carrying the pinion 12 while the intermediate or jack shaft 27 carrying the gear 13 and pinion 14 is journaled in the gear case and is extended through the wall of the case to enable an auxiliary speed to be derived from this shaft, if desired. The gear case is sealed by the covers 31 held on the case by means of screws 32. These covers 10 are not split so that they serve for carrying one half 20 of the gear case when the other half of the case is removed and a support of the case is thus rendered unnecessary. The fitting and dismantling as well as the inspection 15 of the gear is thus greatly facilitated.

Since either heating steam or a cooling medium is supplied to the drum through the longitudinal bore 19 in the shaft stud 17 care must be taken that the gear wheels are 20 as far as possible protected against temperature fluctuations occurring during operations. In the embodiment illustrated in Fig. 1 of the drawings the hub of the spur wheel or gear 15 is for this purpose internally provided 25 with an annular recessed portion 33 so that it is in contact with the shaft stud 17 of the drum with a comparatively small area only.

Instead of providing this recessed portion 30 in the hub of the spur wheel the hub may be mounted upon the stud 17 through the intermediary of an interposed sleeve which consists of a suitable bad conductor of heat and is thus not liable to transmit temperature 35 fluctuations.

To obtain a particularly efficient protection of the gear against temperature fluctuations the hub of the spur wheel 15 may, as shown in Fig. 3 of the drawings, be provided 40 with a large internal recess 34 serving for the reception of a material suitable to insulate against heat. The size of this recess 34 and the nature of the insulating substance may be adapted to be temperature fluctuations 45 developing so that the spur wheel 15 is efficiently protected against temperature fluctuations and the stresses liable to be set up thereby. In some cases it may be advisable to insulate the hub of the spur wheel 15 still further from the drum stud by means of a sleeve. Otherwise the design of the spur wheel remains the same as illustrated in Figs. 1 and 2 of the drawings.

If particularly high temperature fluctuations 50 develop, for instance, if the drum is used for boiling processes in the chemical industry or the like, it is advisable to cool the hub of the spur wheel 15 by special means. Suitable means for effecting this are by way 55 of example illustrated in Fig. 4 of the drawings. The hub of the wheel 15 is here extended outwardly through the gear case in both directions and provided with a circular group of axially directed bores or ducts 41 in communication with a central annular re-

cess 42 in the hub of the wheel 15 so that cooling air is able to enter into the cavity 42. The covers 43 of the gear case are then placed over the extended hub 40 of the spur wheel 15.

The gear designed according to my invention 70 has the advantage that a one-sided additional load on the shaft stud of the drum by the tooth pressure of the gear or wheel 15 is quite eliminated. The driving motor may furthermore easily be exchanged and the entire self-contained gear drive be readily connected and disconnected to and from the driven machine and the motor. Since my improved gear permits the shaft of the roller to readily protrude beyond the gear case, it 75 is particularly suitable for cases in which the interior of the drum is accessible from outside by an axial bore in the shaft.

It will be understood that structural alterations may be made without departing from the spirit of my invention or the scope of the appended claims.

I claim as my invention:

1. In an individual electric drive for internally heated rollers in combination ~~an~~ 90 electric motor, a reduction gear connected to said motor, a casing surrounding said reduction gear and carrying said motor, said roller having a hollow shaft end for supplying a heating medium to the roller, and a gear 95 wheel fixed to said shaft end and journaled in said casing, and having a hollow hub and means contained in the hollow hub portion for preventing the transfer of heat from said shaft end to said gear wheel.

2. In an individual electric drive for internally heated rollers in combination ~~an~~ 100 electric motor, a reduction gear connected to said motor, a casing surrounding said reduction gear and carrying said motor, said roller having a hollow shaft end for supplying a heating medium to the roller, and a gear 105 wheel fixed to said shaft end and journaled in said casing, the hub of said gear wheel protruding at both ends beyond said casing and containing a plurality of axially directed ducts adapted to conduct a cooling medium through said hub for preventing transfer of heat from said shaft end to said gear wheel.

In testimony whereof I affix my signature, 115
ALBERT TACKE.
